UNITED STATES PATENT OFFICE.

PHILIP DIEHL, OF ELIZABETH, NEW JERSEY, ASSIGNOR TO THE SINGER MANUFACTURING COMPANY OF NEW JERSEY.

SEWING-MACHINE.

SPECIFICATION forming part of Letters Patent No. 374,662, dated December 13, 1887.

Application filed April 14, 1887. Serial No. 234,765. (No model.)

To all whom it may concern:

Be it known that I, PHILIP DIEHL, of Elizabeth, county of Union, and State of New Jersey, have invented an Improvement in Sewing-
5 Machines, of which the following description, in connection with the accompanying drawings, is a specification, like letters and figures on the drawings representing like parts.

This invention has for its object the production of a light and very rapid running sewing-machine having an oscillating shuttle contained in an oscillating carrier.

In this my invention the axis of oscillation of the carrier and the shuttle and the center 15 of rotation of the bobbin are substantially coincident with the center of oscillation of the rock-shaft actuating the carrier, and the oscillation of the carrier and shuttle in unison is through an arc in excess of one hundred and 20 eighty degrees of a circle.

The carrier is composed of a skeleton head having a series of arms, which support the heel and point of the shuttle, keep it in upright position, and prevent the shuttle being 25 thrown out of the carrier by centrifugal action, the arms holding the shuttle loosely in such manner that it may be readily passed through the loop of needle-thread, the shuttle being held in a recess at the front of the carrier by 30 a carrier-face, shown as a segmental finger attached to the carrier between that arm which sustains the point and that arm which supports the heel of the shuttle, the shuttle herein shown having a point, and also a loop-dis- 35 charger longer than the point, as described in my application, Serial No. 234,764, filed April 14, 1887, the loop-discharger being perforated for the passage of the needle, thereby enabling 40 a shorter to be used.

My invention is shown as embodied practically in connection with that class of machine represented in United States Patent No. 229,629, dated July 6, 1880.

My invention consists, essentially, in a rock- 45 shaft, D, its attached carrier, a shuttle therein having a beak, and a loop-discharger extended in the direction of but longer than the said beak, a bobbin and a bobbin-case, a needle-bar to carry an eye-pointed needle, a rotat- 50 ing shaft to actuate the needle-bar, and mechanism intermediate the said rotating shaft

and the rock-shaft, to which the carrier is attached, to turn the said rock-shaft and cause the beak of the shuttle to travel at each oscillation through an arc of more than one hundred and eighty degrees, the combination being and operating substantially as will be described.

Other features of my invention will be hereinafter described, and specified in the claims at the end of this specification.

Figure 1 is an under side view of a sewing-machine embodying my invention. Fig. 2 is a rear side elevation of the machine shown in Fig. 1, the frame-work being partially broken out to show the main and other shafts instrumental in operating the needle-bar, shuttle-carrier, feeding mechanism, and take-up; Fig. 3, a left-hand end elevation of the machine or of Fig. 2, looking at it from the side opposite that shown in that figure. Figs. 4, 5, and 5^a are respectively front and side elevations of the carrier. Figs. 6, 7, and 8 are respectively front and side elevations and top or plan views of the shuttle alone. Fig. 9 shows a front and 70 side elevation of the bobbin within the bobbin-case. Fig. 10 is a section of the bobbin-case alone. Fig. 11, a section of the bobbin; Fig. 12, a section in the line x³, Fig. 3, looking up, chiefly to show the bobbin-case holder and its support and the pin or stud on which it is permitted to turn. Figs. 13, 14, and 15 show the needle, shuttle, shuttle-carrier, bobbin-case, and bobbin in different positions, the carrier-face shown in Fig. 1 being broken off to better 85 show the manner of forming the stitch. Fig. 16 is a view of the carrier-face detached, and Fig. 17 the blank from which the carrier is made by forging.

The bed-plate A, the overhanging arm B, 90 the main rotating needle-bar-actuating shaft C, its cam-hub T', the take-up lever T, moved by it, the needle-bar h, carrying an eye-pointed needle, n⁴, the link f, connected to the crank of the shaft C and to the rock-shaft I, the feed-bar K, the feed-bar-lifting rock-shaft E, having arms c' c³ and actuated from a cam, e, on the rock-shaft I, the said cam working between the forks of an arm, c', the feed-regulating rock-shaft F, having arms e e', the lever J, the cam or eccentric d on the shaft C for vibrat- 95 ing the lever J, the devices for altering the 100

throw of the said lever and rock-shaft F to determine the length of stitch, and the shuttle-carrier-actuating rock-shaft D are all as in United States Patent No. 229,629, referred to, wherein the like devices are nearly all designated by like letters, and so, also, I have shown like parts by like letters in my application, Serial No. 234,764, filed April 14, 1887.

The carrier rock-shaft D has at its rear end an arm, p^2 , having a crank-pin, p^3 , that enters a slot or groove in an arm, p^4 , of the rock-shaft I, the center of which bears such relation to the rock-shaft D that as the rock-shaft I is rocked or oscillated by the link f , connected to the arm i^2 of the said rock-shaft and to the rotating shaft C, the shuttle-carrier H, secured to the forward end of the shaft D, will be oscillated through an arc of more than one hundred and eighty degrees (preferably an arc of over two hundred degrees) in one and then in the opposite direction during each complete rotation of the main or operative shaft C during each complete reciprocation of the needle and needle-bar; or, in other words, the beak of the shuttle moves through over four hundred degrees of a circle while the needle-bar-actuating shaft rotates once.

The shuttle-carrier H, made, preferably, from a blank having arms or horns h^2 , h^3 , h^4 , h^5 , and h^6 , and an ear, h^7 , as shown in Fig. 17, is struck up in a die or bent into the shape shown in Figs. 4, 5, and 5^a. The notch 2 in the arm h^2 receives the heel 3 of the shuttle b, and the arm h^3 enters the space between the beak b' and the loop-discharger b^3 of the shuttle b, the said arms h^2 and h^3 acting to support the weight of the shuttle, and by engaging the shuttle at its heel and near its beak, as shown, causes the shuttle to be moved forward through the loop of needle-thread carried by the needle n^4 , and then back into position preparatory to again entering a second loop of needle-thread.

The shuttle b is made as a narrow segmental rim of about one hundred and eighty degrees long, the rim having extended from it one or more arms, 4, one of which carries the post 5, on which is mounted the hollow journal 6 (see Fig. 10, dotted lines) of the bobbin m, carrying the under or second thread, t^3 , the said bobbin being free to be rotated by the pull of the thread upon it; but the bobbin-case g' is restrained from rotation by means of a bobbin-case holder, m^3 , composed of an arm notched at its upper end to engage a lug, g^1 , attached to the front of the bobbin-case. This arm has two like ears, 8, bent from it at right angles, one of which is shown in Fig. 12, the said ears fitting the reduced neck 10 of a stud, 12, depending from the bed-plate, (see Fig. 3,) the lower end of the neck 10 being tapped to receive a screw, 14, the shoulder formed at the junction of the neck 10 and main body of the stud 12 having a pin or projection, 15, (see Fig. 12,) which extends into a slot or notch 65 cut out from the outer edge of one of the ears 8, the pin 15 serving as a stop to limit the

movement of the holder m^3 toward and from the bobbin-case.

One side of the neck is cut away or slabbed off, as shown in Fig. 12, so that a spring, 17, 70 connected to the holder by a screw, 18, may act thereon and keep the holder in position with its notched end in engagement with the bobbin-case.

The bobbin-case is cut away at its front side 75 and beveled, as at g^3 , as shown in my application Serial No. 234,764, so that the loop of needle-thread will be unerringly cast off by the loop-discharger b^3 and by the take-up lever T acting on the thread. 80

The arm h^4 constitutes a rest, against which bears the rear side of the segmental rim of the shuttle b at a point about midway between its heel and beak, the outer side of the said oscillating shuttle being normally pressed toward the inner side of the carrier-face or under thread-guard, n^2 , shown as a segmental finger attached by screws 20 to the lug or ear h^1 , the inner side of the said face n^2 acting to determine the position of the face of the shuttle b, 90 a spring, 22, attached to the said lug by a screw, 23, and acting against the rear side of the shuttle substantially opposite the junction of the beak b' and the loop-discharger b^3 , keeping the point of the beak in just the 95 proper position to insure its entrance into the loop of needle-thread close to and without striking the needle n^4 . The two arms h^5 , h^6 , by extending partially across the shuttle, serve to keep the latter seated on the supporting arms h^2 and h^3 , the said arms h^5 and h^6 overcoming all liability of the shuttle escaping by reason of its centrifugal motion or force appreciable in high speed. 100

The inner side of the carrier-face n^2 or finger 105 is so shaped that the said face n^2 opposite the number 24, Fig. 4, and about opposite the arm h^4 , bears against the outside of the shuttle, thus aiding in keeping the shuttle in proper upright position to co-operate with the 110 needle. 115

The loop-discharger b^3 herein shown, as well as that in my application Serial No. 234,764, receives the loop of needle-thread upon it just as or a little before the point of the beak b' reaches the position Fig. 4. As the loop-discharger advances from the position Fig. 14, the loop of needle-thread is spread over the bobbin-case g' , and just about as the loop of needle-thread crosses the screw 32, the point 120 of the loop-discharger being then in its most forward position, the take-up begins to act and pulls the loop of needle-thread off the loop-discharger and upon the bobbin-case before the shuttle has fully completed its forward movement, the loop being drawn up by the take-up between the heel 3 and the arm h^2 just as the shuttle-carrier commences its return movement, the take-up completing its 125 ascent while the arm h^3 is opposite the needle-hole in the cloth-plate, the needle being elevated out of the work. The arm h^2 will pref- 130

erably have a heel, h^0 , against which may rest the enlarged heel 3 of the shuttle.

The loop-discharger b^3 herein shown is slotted, as at 26, and the beak b' , placed at one side of the loop-discharger, (see Fig. 8,) is concaved, (see Fig. 8,) to form a side point to enter the loop of needle thread when the needle is in the position Fig. 13. The needle h^4 descends through the slot 26 in the loop-discharger b^3 , so that the latter acts as a needle-guard as the beak b' enters the loop, and at such time the face n^2 of the carrier or the segmental finger is interposed between the shuttle and the under thread passing from it to the material.

The tension on the under or bobbin thread is made variable, as desired, by turning a screw, 32, extended through a concavo-convex spring 33, having, as herein shown, two feet, 34 35, and a teat, 36, the latter entering a hole or recess in the bobbin-case.

The feet 34 and 35 rest on the bobbin-case, and the screw 32 enters a concavity (see Fig. 10) in the spring, rotation of the screw to turn it into the bobbin-case increasing the pressure of the upper flat end of the tension spring 33 on the bobbin or under thread, t^3 .

The sharp inward bevel of the foot 34 of the tension-spring aids in accelerating the passage of the loop of needle-thread from the loop-discharger, for between the positions Figs. 14 and 15 the loop of needle-thread is passed beyond the screw 32 and upon the said inclined or beveled foot of the tension-spring, down which it slides, and in so doing is caused to travel off the discharger b^3 very rapidly, the beveled portion of the shuttle and the beveled foot aiding this action very materially.

Holding the shuttle in an oscillating carrier 40 obviates the employment of a raceway in which the shuttle slides, and consequently the shuttle is subjected to the minimum of wear and friction. So, also, by mounting the bobbin and bobbin-case on a stud or post, 5, of the 45 shuttle in line with the center of oscillation of the rock-shaft D, to which the carrier H is attached, the strains exerted by the rapid oscillation of the carrier and shuttle are reduced to the minimum, and so, also, by oscillating the 50 carrier-shaft D and carrier H through an arc of about two hundred degrees during each rotation of the needle-bar-actuating shaft C it is obvious that the beak of the shuttle travels through more than three hundred and sixty 55 degrees of a circle, or through substantially four hundred degrees of a circle, during each stitch, which enables me to utilize a greater proportion of the time used for each stitch for the take-up, and then the feed to operate as 60 stated in my said application, Serial No. 234,764.

I have herein shown and described one well-known form of mechanism between the shafts C and D to enable the latter to be rocked or oscillated from the former as it is rotated; but 65 I desire it to be understood that I do not intend to limit my invention to the exact de-

vices shown, for instead of them I might use any other well-known or equivalent devices by which the shaft D may be rocked for more than one hundred and eighty degrees in one 70 and then back in the opposite direction during each rotation of the shaft C.

In my application Serial No. 234,764, filed April 14, 1887, the outer side of the shuttle is made flat or as a plane surface to run against 75 the smooth guiding-face of the shuttle-race, and consequently the center face of the shuttle is located at one side the path in which the needle reciprocates.

In the machine herein described, having a 80 carrier, A, the shuttle is placed substantially under the needle-hole and in the line of reciprocation of the needle, for by such location of the shuttle the loop of needle-thread when being drawn down is not only more evenly ex- 85 panded, but the loop of thread is drawn from the needle with less side strain on the needle, which in a high-speed machine is very essential.

To enable the shuttle to be placed directly 90 under the needle, the loop-discharger has been slotted to receive the needle when its point is below the throat-plate, and at the same time the said slot enables the shuttle-carrier to be placed nearer the cloth-plate than would be 95 possible were the slot omitted, and as a result thereof it is possible to employ a shorter needle, which is of material practical value.

The free end 43 of the carrier-face n^2 , as shown, is bent inwardly and backwardly to 100 terminate between the periphery of the bobbin-case g' and the shuttle b , thereby preventing the entrance of the under thread, t^3 , between the said shuttle and carrier-face as the shuttle and carrier are moving in their back- 105 ward direction.

The presser-bar, herein marked p , has attached to it a presser-foot, p^6 , both of usual construction.

I claim—

1. In a sewing machine, the following instrumentalities, viz: a rock-shaft, D, its attached carrier, a shuttle therein having a beak and a loop-discharger extended in the direction of but longer than the said beak and 115 pointed toward the periphery of the bobbin-case, the bobbin, the bobbin-case, a central stud to support it and form a center for it about which the bobbin may rotate, a bobbin-case holder to hold the bobbin-case while 120 the shuttle oscillates in one and then in an opposite direction about it, a needle-bar to carry an eye-pointed needle, a rotating shaft to actuate the needle-bar, and mechanism intermediate the said rotating shaft and the rock- 125 shaft, to which the carrier is attached, to turn the said rock-shaft and cause the beak of the shuttle to travel at each oscillation through an arc of more than one hundred and eighty degrees, the combination being and operating 130 substantially as described.

2. The shaft D and its attached shuttle-car-

rier having arms or prongs h^2 , h^3 , h^4 , h^5 , and h^6 and the attached carrier-face or segmental finger, combined with a shuttle, a bobbin-case, and bobbin, and means to restrain the bobbin-case from rotating with the bobbin, substantially as described.

3. The rock-shaft D, its attached carrier having arms to engage and carry a shuttle, a shuttle having a post in line with the center of oscillation of the said rock-shaft and having a beak, b' , and loop-discharger b^3 , combined with a bobbin-case, means to restrain its rotation, and a bobbin, the latter having as its center of rotation the center of the said rock-shaft, substantially as described.

4. The combination, in a sewing-machine, of the following instrumentalities, viz: a needle-bar to carry an eye-pointed needle, a rotating shaft to actuate it, a shuttle-carrier rock-shaft, D, means intermediate it and the said rotating shaft to oscillate the rock-shaft for more than one hundred and eighty degrees, a carrier having a series of arms or prongs to sustain and carry a shuttle, a shuttle having a heel, a beak, a loop-discharger, and a post, 5, and a bobbin and bobbin-case, the loop-discharger discharging the loop of needle thread upon the bobbin-case at a point beyond a vertical line drawn through the center of the rock-shaft and bobbin-case, substantially as described.

5. In a sewing-machine, a rock-shaft, an attached carrier having arms to hold a shuttle, a shuttle having a heel, a beak, b' , and a forwardly-extended loop-discharger, the point of which extends beyond the said beak, a bobbin-case and bobbin, and a carrier-face attached to the carrier and extended back from the beak of the shuttle to act upon the outer face of the shuttle between its ends, the combination being and operating substantially as described.

6. In a sewing-machine, a rock-shaft, an attached carrier having arms to hold a shuttle, a shuttle having a heel, a beak, b' , and a forwardly-extended loop-discharger, the point of which extends beyond the said beak, a bobbin-case and bobbin, and a carrier-face attached to the carrier and extended back from the beak of the shuttle to act upon the outer face of the shuttle between its ends, and with a spring to act against the shuttle near the base of its beak, substantially as described.

7. The rock-shaft D, its attached carrier having arms to hold the shuttle, the shuttle having a heel, a beak, b' , a slotted loop-discharger, and a post, 5, in line with the axis of the said rock-shaft, the face n^2 , the bobbin-case beveled as at g^3 , the bobbin m , means to restrain the bobbin-case from rotation, the

needle-bar, means to move it, and a take-up to take up the loop of needle-thread as it is discharged from the loop-discharger, the parts being combined to operate substantially as described.

8. The rock-shaft D, its attached carrier having arms, as described, and a carrier-face, n^2 , to hold the shuttle, combined with a bobbin-case, a bobbin, a shuttle having a beak, a loop-discharger, b^3 , longer than the beak and terminating near the bobbin-case, all as shown and described, to discharge the loop of needle-thread on the bobbin-case beyond a vertical line drawn through its center, and a tension device, substantially as described, connected to the bobbin-case.

9. The bobbin-case, the bobbin, and the shuttle, combined with the tension-spring 33, having feet 34, 35, and 36, and with a screw, 32, the foot 34 and the bobbin-case being beveled, all as set forth, to give up the loop of needle-thread quickly, substantially as described.

10. In a sewing-machine, an eye-pointed needle, means to reciprocate it, an oscillating shaft provided with a shuttle-carrier, a shuttle having a beak and a loop-discharger extended in advance of the beak, and a post, 5, combined with a bobbin-case holder, a bobbin-case, and a bobbin mounted on the said post, the said post being located in line with the center of oscillation of the said oscillating shaft, to operate all substantially as described.

11. The bobbin-case and tension-spring having a thread-pressing end and feet, and a seat, 36, to support one part of the tension-spring between its ends from contact with the said bobbin-case and provided with a concavity, combined with a tension-regulating screw, the head of which enters the said concavity, thereby preventing the needle-thread catching upon the said screw, substantially as described.

12. The oscillating carrier and shuttle therein, combined with the carrier-face secured to and moving with the carrier, the said carrier-face having an inwardly-bent free end terminating between the periphery of the bobbin-case and the periphery of the shuttle to prevent the entrance of the bobbin or under thread under the said face as the carrier and shuttle are being moved backward, substantially as described.

In testimony whereof I have signed my name to this specification in the presence of two subscribing witnesses.

PHILIP DIEHL.
